(54) **BOILER, CONSTRUCTING**

(76) Inventor: **Joseph Jr. Hurd**

Joseph Ward, Jr.

The Schedule referred to in these Letters Patent, is making, part of the same, containing a description in the words of the said Joseph Ward, Jr. himself, of his improvement in the construction of ovens with reflectors.

To all persons to whom these Presents shall come, Joseph Ward, Jr. of Harbor, in the County of Suffolk, & State of Massachusetts, Gutterman, and creating, No. 12 known, that I, the said Joseph Ward Jr. have made and applied to me, a new and useful improvement in the construction of ovens, by applying to them polished tin or other metal, as reflectors by means whereof, the waste of heat is in a great measure prevented, called an oven with Reflectors. See Fig. 1 & 2, in the Plate. This improvement consists principally in the application of this metal polished tin, arranged around or partially around the oven, which will reflect back upon it, the heat which would otherwise be lost by radiation or absorption according to the material made use of. The following description of an oven with reflectors, sufficient for a family of 8 to 10 persons will shew the manner in which they are constructed. Take for the bottom of the oven a cast iron plate. See Fig. 1. a. a. a. The front straight & 20 inches. The sides straight and 10 inches. The back - The back semicircular. The top of the oven b. b. b. and its sides are of that iron, the joints locked or riveted together. It height 10 inches. This oven is enclosed except its front, in a box of cast of that iron; having, the form of the oven, but standing 2 feet high, being so much larger than the oven as to have an intermediate space between the sides & back of 2 inches. See Fig. 1. d. d. d. d. This case should have a cast iron front, & 24 inches square, in which there must be an opening, for the mouth of the oven, 20 inches by 10. It should be 4 inches from the top of the plate in front, See Fig. 1. M. M. The mouth of the oven is to be directed to the front of the case at this opening, & should be perfectly secured in its place by having a bar of iron just under the back part of it, the end of which shall be riveted to the oven. A door Fig. 1. C, must be fitted to the oven, having, a small hole high the bottom to let in air; which should have a slide to close it. Fig. 1. f. There should also be a hole of about 2 inches high in the top of the oven, to which should also have a slide. A tube Fig. 1. g. Should be fitted to it, leading into the flue, or back this the case, to carry the vapor from the oven.

Fig 1. e. e. e. Parallel to the top of the oven, and 2 inches above it, there must be a plate, or sheet of iron fitted to the form of the outer case except that it should come within 2 inches of the front of the case. The edge of the plate should be secured to the case by rivets, or otherwise. The smoke will pass between the oven top and this plate, down to the flue. There

should be a circular opening of about 2 inches in the front plate, immediately over the oven, to introduce a brush or scraper to clean out soot. Figs. h, h, a cap or stopper must be fitted to it, at the bottom of the front plate under the oven, there must be a square opening 8 inches broad & 7 inches high Fig. i, i, & a door, k, fitted to it. This, then the pot is dropped into the furnace. A hole with a well to receive ~~the furnace~~ must be fitted close & riveted upon this case Fig. l, l, l. Should that iron be used for the front, it should have a well to give it firmness. Plate of iron or other polished metal Fig. 2, of the same form as the back iron case, but so much larger as to have an intermediate space of 3 inches, must be fitted over the whole. A square opening Fig. 2. a, a, a, a, should be left to get at the door k, which may be closed by a door, b, b. A hole c for the funnel & other holes &c, &c, may be left for ventilation, the bottoms of which will rest upon the top of the case.

When heat is wanted to warm an apartment, part of the reflector may be taken off, for which purpose it may be made in detached pieces, or it may have doors at the sides to be opened & closed. This case & oven should be so placed over a furnace, as to exclude all air except that passes thro' the fire. It is particularly calculated for the furnace with reflectors lately invented. The construction of the case above described, appears most suitable for culinary purposes.

The material, size, form, and proportions may be varied at pleasure, so as to be most suitable to manufacturers, mechanics & others. It is unnecessary to mention the various modes in which reflectors may be applied to heat in heat and constitute what may be called an oven, in the sense in which it should be understood in this specification.

I testify that the above is a true specification of my said improvement, as above described, I have hereunto set my hand and seal, the twentieth day of October in the year of our Lord one thousand eight hundred and twenty nine.

Joseph Ward Jr.
